UNITED STATES PATENT OFFICE.

WILLIAM T. BAILEY, OF BRADFORD, PENNSYLVANIA.

COMPRESSOR.

Application filed January 2, 1925. Serial No. 219.

This invention relates to oil wells and has for an object the provision of a cheap, novel and efficient method for forcing water and air (either together or separately) through the sand rock for the purpose of forcing oil into other wells.

Heretofore it has been customary to fill the well tubing with water and to depend upon the pressure of the column of water thus formed, to force the oil through the sand, or to force air under pressure into the tubing by means of compressors. The first method is exceedingly slow, while the second method is expensive as the compressors must be kept in constant operation.

The method which constitutes the present invention utilizes both air and water in such a way that a constant and sufficient pressure is provided which will readily force the oil through the sand rock, while the expense of the operation is reduced to a minimum.

With the above and other objects in view, the invention further includes the following novel features and details of construction, to be hereinafter more fully described, illustrated in the accompanying drawings and pointed out in the appended claims.

In the drawings:—

Figure 1 is an elevation showing the invention arranged for use in connection with an oil well, the casing of which is shown in section.

Figure 2 is a view showing the invention in section.

Figure 3 is an enlarged detail sectional view on the line 3—3 of Figure 1.

Figure 4 is a similar view on the line 4—4 of Figure 1.

Referring to the drawings in detail wherein like characters of reference denote corresponding parts, the reference character 10 indicates the casing of an oil well within which extends the tubing 11.

The invention comprises a cylinder 12 which is provided at its lower end with a head 13, while extending from the latter is a reduced tubular portion 14 connected to the tubing 11 by a union 15. Thus the cylinder 12 is in communication with the tubing 11.

The cylinder 12 as shown is vertically arranged and is provided with a piston 16, the latter being preferably equipped with the usual packing rings. Extending from the

piston 16 through the top of the cylinder 12 is a piston rod 17. Adjustably mounted upon this rod is a cross head 18 which operates over guides 19 extending from the top of the cylinder.

The cylinder 12 is supported by upper and lower inclined braces 20 which are anchored to suitable timbers 21, while the guides 19 have their upper ends adjustable to guy rods 22.

Air from a suitable source may be admitted to the cylinder 12 through a pipe 24 which is controlled by a valve 25, while a blow off cock 26 is provided to relieve pressure within the cylinder. The cylinder is provided with an air gauge 27.

The tubing 11 is provided with a plurality of check valves 28 whereby water may be admitted from the casing into the tubing, but pressure within the tubing will close the valves.

In operation, the tubing 11 is filled with water and air under pressure is admitted to the cylinder 12 by opening the cock 25. The piston 16 will then be forced upward within the cylinder until the proper air pressure is indicated on the gauge 27. The desired number of weights 23 is then placed upon the cross head 18 so that the piston is forced downward within the cylinder and air under pressure from the latter is forced into the tubing 11 on top of the column of water therein. A constant water and air pressure is thus provided without the necessity of continuous operation of compressors for this purpose.

The invention is susceptible of various changes in its form, proportions and minor details of construction and the right is herein reserved to make such changes as properly fall within the scope of the appended claims.

Having described the invention, what is claimed is:—

1. Means for forcing oil through sand rock and the like comprising in combination with the well tubing having a column of water therein, an air cylinder in communication with the tubing and weight operated means for forcing air from the cylinder into the tubing.

2. Means for forcing oil through sand rock and the like comprising in combination with the well tubing having a column of water therein, a vertically disposed cylinder mounted above and communicating with the

tubing and a weight operated piston movable within the cylinder for forcing air from the cylinder into the tubing.

3. Means for forcing oil through sand rock and the like comprising in combination with the well tubing having a column of water therein, a vertically disposed cylinder mounted above and communicating with the tubing, a piston movable within the cylinder, a rod extending from the piston above the cylinder, guides extending upwardly from the cylinder, a cross head carried by the rod and operatively engaging the guides and a weight mounted upon the rod and

supported by the cross head for operating 15 the pistons to force air from the cylinder into the tubing.

4. The method for forcing oil through sand rock consisting of filling the well tubing with water, subjecting the column of 20 water in said tubing to a predetermined air pressure from a suitable source, cutting off the supply of air from said source and thereafter maintaining substantially constant weight controlled air pressure for an ap- 25 preciable period.

In testimony whereof I affix my signature.

WILLIAM T. BAILEY.
